United States Patent

Des. 236,294
Patented Aug. 19, 1975

236,294

NECKTIE

Robert R. Newell, 2828 N. Atlantic Ave.,
Daytona Beach, Fla. 32018

Filed Jan. 29, 1974, Ser. No. 437,544

Term of patent 14 years

Int. Cl. D2—02

U.S. Cl. D2—351

FIG 1

FIG 2

FIG. 1 is a plan view of a necktie showing my new design, the adjusting element being conventional and the side opposite to that shown being otherwise identical thereto; and

FIG. 2 is a front elevational view thereof in wearing position.

I claim:

The ornamental design for a necktie, as shown and described.
